M. J. HOGAN

INTERCHANGEABLE CHARACTER CONSTRUCTION

Filed Dec. 12, 1921

Inventor:
Michael J. Hogan
By Jones, Addington, & Son, Attys.

UNITED STATES PATENT OFFICE.

MICHAEL J. HOGAN, OF CHICAGO, ILLINOIS.

INTERCHANGEABLE-CHARACTER CONSTRUCTION.

Application filed December 12, 1921. Serial No. 521,582.

To all whom it may concern:

Be it known that I, MICHAEL J. HOGAN, a citizen of the United States, residing at Chicago, in the county of Cook and State of Illinois, have invented new and useful Improvements in Interchangeable-Character Constructions, of which the following is a full, clear, concise, and exact description, reference being had to the accompanying drawing, forming a part of this specification.

My invention relates to interchangeable character construction.

One of the objects of my invention is to provide an improved interchangeable character construction which can be worked out in metal so as to give a solid substantial appearance both from the front and back, such a construction being desirable for high grade office use, banks, building directories, memorial tablets, and the like.

A further object of my invention is to provide an improved interchangeable character construction suitable for use as indicated above, in which the slot in the metal tablet will be closed in the rear by an integral part of the metal tablet, thereby preventing foreign substances from getting into the slot from the rear.

30 A further object of my invention is to provide improved means whereby the characters may be forced snugly against each other to close up the spaces or cracks between the characters and hold them snugly in place.

Further objects will appear from the detailed description to follow and from the appended claims.

In the drawings in which two embodiments of my invention are shown—

Figure 1 is a front elevational view of a desk sign;

Fig. 2 is a front elevational view of the plate without end support and characters;

Fig. 3 is an end elevational view of one of the end supports;

Fig. 4 is a section on the line 4—4 of Fig. 1;

Fig. 5 is a section on the line 5—5 of Fig. 2;

Fig. 6 is a sectional view substantially on the line 6—6 of Fig. 1;

Fig. 7 is a perspective view showing the back side of one of the characters;

55 Fig. 8 is a perspective view showing the front side of one of the characters;

Fig. 9 is a front elevation showing my invention as applied to a building directory;

Fig. 10 is a section on the line 10—10 of Fig. 9; and

Fig. 11 is a section on the line 11—11 of Fig. 9.

Referring first to Figs. 1 to 7 inclusive, the construction shown therein comprises a pivotally mounted name-plate or desk-plate 10, on which are detachably mounted the interchangeably type blocks 11. The construction is such that the type blocks can be readily removed and replaced by others whenever desired, as when a change in personnel is made. The construction is such that it can hardly be noticed that the characters are not cast as an integral part of the supporting plate, the entire appearance being solid and substantial looking.

The plate 10 may, if desired, be a bronze casting, having a longitudinally extending slot 12 milled therein to receive the hook-shaped shanks 13 of the characters 11.

In order to provide for the entry of the hook-shaped shanks 13 into the angular slot 12, a recess 14 is provided at one end of the plate 10, adjacent the slot 12, to permit the entry of the shank 13 at this point. After the shank 13 has entered the recess 14, the type block is dropped down to engage the point of the hook 13 underneath the upwardly extending lip 15 (Fig. 5). The characters can then be slipped along the slot 12 to their proper position on the plate. As shown in Figs. 4 and 5, the slot 12 is open on the front face of the plate, but is completely closed by the material of the plate in the rear of the slot, so that foreign substances cannot enter the slot from the rear of the plate. This construction also gives a neat appearance to the rear of the plate.

In order to press the type blocks firmly against each other, to close up the gaps or cracks between them, and give the type blocks the appearance of being practically integral with the supporting plate 10, a pair of screws 16 are provided, one at each end of the tablet, each having a threaded engagement with the supporting plate 10, and having a point bearing on the edge of one of the type blocks 11 (Fig. 6).

These screws 16 serve not only to clamp the type blocks in position, but also serve to pivotally support the plate 10 on the end brackets 17, as the screws extend through

the bearing openings 18 in these end brackets.

In using the device, if it is desired to change the name or other characters on the tablet or plate 10, the screws 16 are loosened up to free the type blocks, and the type blocks can then be removed one at a time, by sliding them to the right end of the tablet or plate 10, until the shanks 13 are opposite the recess 14, when they can be pulled forwardly out of engagement with the plate.

In Figs. 9, 10 and 11, my invention is shown applied to a directory, such as is used in large office buildings. The construction shown in these figures comprises the large plate 19, which may be of bronze or other suitable material, the type blocks 20, mounted on the plate 19, and the screws 21 threaded into the plate 19, and bearing 20 on the type blocks 20 for holding them snugly against each other, the construction and operation of these blocks being the same as the construction and operation of the corresponding parts of the construction previously described. The heads of the screws 21 may be located in channels 22, in the plate 19, and may have squared ends for engagement with a wrench or other suitable tool for tightening them up. The heads of 30 these screws may be concealed from view by means of a cover plate 23 secured to the plate 19 by means of screws 24, provided with ornamental heads or handles 25, for giving an ornamental appearance to the board, and for use in operating the screws 24.

In this form of my invention, if it is desired to change one of the names, the cover-plate 23 may be removed giving access to the screws 21, which are then loosened up to permit the type blocks 20 to be

slid longitudinally to the end of the groove where they can be disengaged just as in the construction first described.

While I have shown but two embodiments 45 of my invention, it may be embodied in other forms covered and defined in the appended claims.

Having thus described my invention what I claim as new and desire to secure by Letters Patent of the United States is:

1. An interchangeable character construction, comprising a tablet having a slot therein, and a plurality of characters each having a hook-like shank engageable in said slot, said tablet comprising an integral metal plate in which the slot is located, having a longitudinally extending lip overhanging a portion of said slot for retaining said hook-like shank, said slot being open on the front face of said integral metal member, the material of said integral metal plate extending across and closing the rear of said slot to prevent foreign material from entering said slot from the rear and to provide a finished appearance to the rear of said tablet.

2. An interchangeable character construction comprising a plate having a slot therein, and a plurality of characters having a hook-like shank engageable in said slot, and means for pivotally supporting said plate and forcing said letters snugly against each other, comprising a support and a pivot screw threaded into said support for pivotally supporting the plate, and for bearing on one of the characters to force it longitudinally of said slot.

In witness whereof, I have hereunto subscribed my name.

MICHAEL J. HOGAN.
